UNITED STATES PATENT OFFICE.

DAVID E. ROSS, OF BROOKSTON, INDIANA, ASSIGNOR TO ROSS GEAR AND TOOL COMPANY,
OF LA FAYETTE, INDIANA, A CORPORATION OF INDIANA.

AXLE.

No. 893,549.

Specification of Letters Patent.

Patented July 14, 1908.

Application filed September 11, 1906. Serial No. 334,128.

To all whom it may concern:

Be it known that I, DAVID E. ROSS, a citizen of the United States, residing at Brookston, in the county of White and State of Indiana, have invented a certain new and useful Improvement in Axles, of which the following is a full, clear, and exact description, reference being had to the accompanying drawings.

10 This invention relates to an axle for vehicles, and more particularly to the rear axle for self-propelled vehicles, the object of the invention being the strengthening and cheapening of the construction of such axles, 15 and at the same time making it possible to assemble the driving devices for said axles with ease. I attain these objects by forming the axle in one continuous piece, the cross section of the axle being in the form of an 20 I-beam with the upper and lower sides extended at the center so as to give the necessary strength and clearance for the driving mechanism.

Referring to the drawings, Figure 1 is a 25 rear elevation of my axle, the cap plate for the driving mechanism being shown in position. Fig. 2 is a sectional view through the center of Fig. 1 on the line 2—2; Fig. 3 is a transverse sectional view taken through 30 Fig. 1 on the line 3—3 and looking in the direction of the arrows; Figs. 4 and 5 are views of a clutch mechanism which I have shown applied to my axle; and Fig. 6 is a modification in which the spindles are separate 35 from the other parts of the axle.

Taking up the description of the invention in detail, 1 represents a tubular portion of the axle which extends from end to end thereof, and has upon its opposite ends the spindles or bearings 2 for the vehicle wheels, one 40 of said wheels being indicated in dotted lines at the right in Fig. 2. At the inner ends of the spindles 2 there are cast, integrally with the remainder of the axle, flanges 45 or disks 3, said disks forming means of attachment for braking devices which operate against the inner side of a flange on the hubs of the vehicle wheel, as indicated in Fig. 2. These braking devices may be of any suitable 50 type, but, as shown, they consist of a split friction ring 4 that is expanded into engagement with the hub of the vehicle wheel by a rocking member 5 carried by the disk 3, said member being rocked by a crank 6 and rod

7 that may be attached to any suitable form 55 of operating device.

Extending in vertical planes both above and below the tubular member 1 is a web 8, said web connecting the tubular member at the center with the outer flanges 9, said 60 flanges being at right angles to the plane of the web, and extending on each side thereof, so that the flanges with the web form an I-beam. As shown in Fig. 1, the web 8 increases in depth from the disks 3 to the center of the axle, so that the axle has the proper depth at the center to afford the necessary strength of construction, and at the same time give the proper clearance for the driving devices for the axle. These driving devices may be of any desired type, such as beveled gears meshing with driving beveled pinions, or they may be a sprocket wheel driven by a chain. In the drawing I have indicated in dotted lines the former kind of driving 75 mechanism, the beveled gears being shown at 10 and 11 and the driving pinions therefor at 12 and 13. In front of these gears and their hubs, the web 8 is turned forwardly so as to form a housing at 14, said housing being cast 80 or otherwise formed integrally with the web and the other portions of the axle structure. At the rear of the gears 10 and 11 the housing for the gears is formed of a cap plate 15 that is adapted to be bolted or otherwise secured 85 to the remainder of the axle, said cap plate forming with the axle proper a receptacle for the gearing which may be made of sufficient tightness to contain oil within which the gears operate. When the form of gearing indicated in Fig. 2 is employed, the housing 14 is provided on one of its inner faces with a projecting ledge 16 within which a bearing 90 for the inner end of the drive shaft may be formed. When a sprocket gear is employed, 95 however, this ledge would preferably be omitted.

The vehicle wheels are connected with the driving gears or other driving mechanism by axle sections which extend through the tubular portion 1 of the axle, said axle sections having a driving engagement with the driving mechanism at their inner ends and with the wheels at the outer ends. Such a construction is shown in my pending application 10 No. 311,465, and need not be specifically described herein.

The opening closed by the cap plate 15 is

- of sufficient size to permit the insertion from the rear of the driving mechanism, so that in assembling the parts it is merely necessary to insert the driving mechanism and then insert 5 the axle sections, after which the cap plate may be secured in position. It will of course be understood that the hubs for the driving gears 10 and 11, or other driving mechanism, form one part of a roller bearing, said rollers 10 turning within the enlarged portion 17 of the tubular part 1, and the hub-like extension 18 of the cap plate 15.
- While it is believed that the structure shown and described is of ample strength, I 15 contemplate extending truss or strengthening rods 19 from the flanged disks 3 to the housing 14. Such a construction would be useful only in case a sprocket wheel construction is employed for driving.
- 20 Instead of forming the spindles integrally with the remainder of the axle, they may be made of steel and forced into sockets cast in the ends of the axle proper. This modification is illustrated in Fig. 6 of the drawings.
- 25 I claim:
1. As a new article of manufacture, an axle made in the form of an I-beam, said axle being formed of a single piece, and having a receptacle for the gears within the flanges of 30 the I-beam.
  2. As a new article of manufacture, an axle made in the form of an I-beam, said axle being cast in a single piece, and having a receptacle for the gears within the flanges of 35 the I-beam.
  3. As a new article of manufacture, an axle formed of a single piece and having exterior flanges connected by a web so as to form in 40 cross section an I-beam, said axle increasing in depth from its ends to its center.
  4. As a new article of manufacture, an axle cast in a single piece and having exterior flanges connected by a web so as to form in cross section an I-beam, said axle increasing 45 in depth from its ends to its center.
  5. An axle formed of a single piece and having spindle bearings at its ends, disks at the inner end of said spindle bearings, a web extending between said disks, said web being 50 transferred for a portion of its length to form a housing for drive gears and flanges at the outer edges of said web.
  6. An axle cast in a single piece and having spindle bearings at its ends, disks at the inner end of said spindle bearings, a web extending between said disks, said web being transferred for a portion of its length to form a housing for drive gears and flanges at the outer edges of said web.
  7. An axle formed of a single piece and having a cross section in the shape of an I-beam, with a housing integral with the axle, on one surface for the reception of the driving mechanism.
  8. An axle cast in a single piece and having a cross section in the shape of an I-beam, with a housing cast on the front surface for the reception of the driving mechanism. 65
  9. An axle cast in a single piece and having at its opposite ends spindle bearings for the vehicle wheels, a tubular portion in line with said spindles for containing the axle sections, a web extending in vertical plane from said tubular portion, strengthening flanges at the outer edges of said web, a housing projecting 70 from the center of said web, in combination with a cap plate adapted to be secured to the face of the web opposite said housing.
  10. An axle cast in a single piece and having at its opposite ends spindle bearings for the vehicle wheels, brake-supporting disks adjacent said spindle bearings, a tubular portion in line with said spindles for containing the axle sections, a web extending in vertical plane from said tubular portion, strengthening flanges at the outer edges of said web, a housing projecting forwardly from the center of said web, in combination with a cap plate 75 adapted to be secured to the rear face of the web opposite said housing. 80
  11. An axle cast in a single piece and comprising spindles at its opposite ends, disks at the inner ends of said spindles, tubular portions in line with said spindles, for containing the axle sections, a web extending from said tubular portions in vertical plane, said web increasing in depth from its ends toward its center, a flange at the outer edges of said web and forming therewith an I-beam, a housing for the driving mechanism cast on the 85 side of said web, a ledge cast within said housing, said ledge forming a bearing for a drive shaft for the driving mechanism and a cap plate cast separately from the axle structure and adapted to be secured thereto opposite the said housing, said cap plate forming with the housing a receptacle for the driving mechanism. 90
  12. An axle cast in a single piece and comprising spindles at its opposite ends, disks at the inner ends of said spindles, tubular portions in line with said spindles for containing the axle sections, a web extending from said tubular portions in vertical plane, said web increasing in depth from its end toward its center, a flange at the outer edges of said web and forming therewith an I-beam, a housing for the driving mechanism cast on the 95 forward side of said web, a ledge cast within said housing, said ledge forming a bearing for a drive shaft for the driving mechanism, a cap plate cast separately from the axle structure and adapted to be secured thereto opposite the said housing, said cap plate forming with the housing a receptacle for the driving mechanism. 100
  13. An axle cast in a single piece and comprising spindles at its opposite ends, disks at the inner ends of said spindles, tubular portions in line with said spindles for containing the axle sections, a web extending from said tubular portions in vertical plane, said web increasing in depth from its end toward its center, a flange at the outer edges of said web and forming therewith an I-beam, a housing for the driving mechanism cast on the 105 forward side of said web, a ledge cast within said housing, said ledge forming a bearing for a drive shaft for the driving mechanism, a cap plate cast separately from the axle structure and adapted to be secured thereto opposite the said housing, said cap plate forming with the housing a receptacle for the driving mechanism. 110
  14. An axle cast in a single piece and comprising spindles at its opposite ends, disks at the inner ends of said spindles, tubular portions in line with said spindles for containing the axle sections, a web extending from said tubular portions in vertical plane, said web increasing in depth from its end toward its center, a flange at the outer edges of said web and forming therewith an I-beam, a housing for the driving mechanism cast on the 115 forward side of said web, a ledge cast within said housing, said ledge forming a bearing for a drive shaft for the driving mechanism, a cap plate cast separately from the axle structure and adapted to be secured thereto opposite the said housing, said cap plate forming with the housing a receptacle for the driving mechanism. 120
  15. An axle cast in a single piece and comprising spindles at its opposite ends, disks at the inner ends of said spindles, tubular portions in line with said spindles for containing the axle sections, a web extending from said tubular portions in vertical plane, said web increasing in depth from its end toward its center, a flange at the outer edges of said web and forming therewith an I-beam, a housing for the driving mechanism cast on the 125 forward side of said web, a ledge cast within said housing, said ledge forming a bearing for a drive shaft for the driving mechanism, a cap plate cast separately from the axle structure and adapted to be secured thereto opposite the said housing, said cap plate forming with the housing a receptacle for the driving mechanism, and a strengthening rod extending between said disks and the housing. 125

13. In an axle structure formed of a single piece and having a cross section in shape of an I-beam with the vertical web transferred for a portion of its length to form a housing 5 for drive gears, and a cap placed on the side of the web opposite the housing to complete the latter.

In testimony whereof I affix my signature in the presence of two witnesses.

DAVID E. ROSS.
